CHARLES M. MANLY, OF WASHINGTON, DISTRICT OF COLUMBIA.

FLUID-PRESSURE ADJUSTING MECHANISM.

No. 801,096.

Specification of Letters Patent.

Patented Oct. 3, 1905.

Application filed August 20, 1902. Serial No. 120,415.

To all whom it may concern:

Be it known that I, CHARLES MATTHEWS MANLY, a citizen of the United States, and a resident of Washington, District of Columbia, 5 have invented certain new and useful Improvements in Fluid-Pressure Adjusting Mechanisms, of which the following is a specification.

My invention relates to a pressure-operated synchronous adjusting mechanism in which a 10 fluid-pressure motor controlled by a valve is interposed between a source of fluid-pressure supply and a mechanism requiring rather powerful and frequent adjustments.

My object is to provide simple and effective 15 means in such mechanism as that designated for adjusting at will relatively fixed elements of a mechanism on which considerable forces may be acting by the simple movement of a controlling-valve requiring a practically negligible force for its operation.

My further object is to accomplish this desirable result in such a way that the relatively fixed elements on which the considerable force may be acting will be adjusted at all times and 25 in either direction in proportion to the movement of the controlling-valve and that such elements when so adjusted will remain fixed against extraneous forces tending to change their adjustment until their positions are 30 changed by the movement of the controlling-valve, and, finally, my object is to provide such an adjusting mechanism that the pressure-operated motor which adjusts the relatively fixed elements of any mechanism which 35 it is desired to adjust will make such adjustments practically simultaneously and synchronously with the adjustments or movements of the controlling-valve.

With these objects in view my invention 40 consists in the combination, with a variable-speed gear comprising a pump and motor, of a fluid-pressure adjusting-motor and connections between said motor and variable-speed gear whereby the said gear may be adjusted 45 for different speeds, and, further, in the combination, with such a variable-speed gear, of a fluid-pressure adjusting-motor and a valve mechanism, one element of which is adjustable at will and another element of which is connected to said adjusting-motor, one of which elements is provided with a fixed part normally out of operative connection with, but adapted to be connected to, such other element; and my invention further consists in 55 the novel construction and details thereof, as hereinafter described with reference to the

accompanying drawings and more particularly pointed out in the claims.

In the drawings, which illustrate a preferred form in which my invention may be carried 60 out, I have shown the adjusting mechanism as used in connection with a variable-speed gear, such as described and claimed in my Letters Patent No. 710,485, dated October 7, 1902. 65

Figure 1 is a side elevation of my adjusting mechanism applied to a variable-speed gear with the front half of the relief-chamber thereof removed to show the fluid-pressure connection between the speed-gear and the adjusting-motor. Fig. 2 is a sectional plan view on the line 2 2, Fig. 1, looking in the direction of the arrow. Fig. 3 is a sectional end view of the adjusting mechanism on the line 3 3, Fig. 1, looking in the direction of the arrow. 70 Fig. 4 is a detached side elevation of the secondary valve. Fig. 5 is an end elevation thereof looking in the direction of the arrow, Fig. 4. Fig. 6 is an end elevation of the primary regulating or controlling valve looking in the 75 direction of the arrow in Fig. 3. Fig. 7 is a sectional plan view of the distributing-valve and relief-chamber of the speed-gear. Fig. 8 is a perspective view of the primary regulating-valve, and Fig. 9 is a perspective view of 80 the secondary valve.

While in the drawings I have shown my new adjusting mechanism as connected to a speed-gear, yet it is to be understood that I do not confine my present invention to a use 90 in combination with a variable-speed gear, such a combination being adopted herein mainly for the purpose of more clearly illustrating an important and valuable relation in which my adjusting mechanism may be used. 95

Such parts of my variable-speed gear are shown in the drawings as will clearly illustrate the manner of applying my present invention thereto. This speed-gear consists, essentially, of a rotary reciprocating pump 100 driven from any suitable external source of power, a rotary reciprocating motor connected to said pump by a fluid and adapted to be operatively connected with a driven device, and means for varying the relative capacities of 105 the pump and motor whereby the speed of the driven device may be varied at will with respect to that of the driving device. I will now indicate, briefly, the parts of such a speed-gear, referring to the drawings, in which the 110 same reference characters relate to the same or corresponding parts in all the views.

The letter I indicates portions of the fixed framework, in which the stationary valve structure E is fixedly mounted. The valve structure is provided with two semicircular ports P and P', consisting of cored passages extending through the same and terminating in the inner faces of annular flanges projecting from the central web of the valve. The ports and constituent passages are separated from each other by narrow bridges or partitions G at diametrically opposite points. A, A', A², A³, A⁴, and A⁵ are the pump-cylinders, mounted so as to rotate in contact with the valve structure, and each is provided with a port adapted to register successively with the ports P and P' of the valve structure, while similarly disposed on the other side of the said valve structure are rotary motor-cylinders A₁, A₂, &c. The pump-cylinder structure is adapted to be connected to a driving device through the medium of a sprocket S, fixed to the hub of the rotary-cylinder structure, and in like manner the motor-cylinder structure may be connected by a sprocket S₁ to a driven device. The motor-cylinder and pump-cylinder structures are mounted in independent bearings on the fixed frame, the letter K indicating the end of one of the trunnions of the motor-cylinder structure, surrounded by a bush L. The crank-pin C, to which the connecting-rods of the pistons (not shown) in the cylinders A, A', &c., are connected, is carried by a shaft N, mounted in the eccentric bore of a bush M, the latter of which is concentrically mounted in the trunnion-bearing of the cylinder structure. A spur-gear Q is fixed to the bush M by a suitable spline q, and a spur-gear T is fixed to the shaft N by a suitable spline t, and the said gear T meshes with the internal teeth R on the spur-gear O, rotatably mounted on the bush M. The crank-pin C may be caused to move radially toward and through the central axis of the device by proper relative motion of the shaft N and the bush M in opposite directions, such motions being imparted, preferably, through the medium of the racks W and Y, as hereinafter more particularly described, or through any other suitable mechanism, and operated by the adjusting mechanism. The motor-cylinders A, A₁, A₂, &c., are constructed similarly to the pump-cylinders and have corresponding ports adapted to register with the ports P and P', and their pistons are connected to a crank-pin one hundred and eighty degrees from the pin C, which pin is carried by a shaft similar to the shaft N and mounted in a corresponding bush, on the latter of which is fixed a spur-gear Q₁, and on the shaft is a gear corresponding to the gear T and meshing with internal teeth on a gear O₁, so that adjustment of the crank-pin of the motor structure may be effected in a similar manner to the crank-pin C. The interior space of the valve and cylinder structures and

the passages between the two cylinder structures are to be supplied with fluid, such as oil or water, providing a fluid connection between the pump and motor, and the operation of the device as a variable-speed gear will be clearly understood by those skilled in the art. To relieve excess of fluid in the fluid connection, due to any cause, the relief-chamber d, Fig. 1, is provided, which chamber is connected to the two ports P and P', respectively, through the medium of the ports s and s'. A piston-valve V, having heads h and h', is adapted to reciprocate in said chamber, the movement of the valve in either direction being limited by fixed stops u and u', carried by the closing-plugs r and r'. Cored passages terminating in ports e and e' are formed in the chamber next to the valve structure E, such ports being so located as to connect the ports P and P' through the passages s and s' with the port f, which communicates through a suitable passage with the central space of the structure or reservoir, such connections being established by the movement of the valve V when excess fluid-pressure on either end of the valve causes it to move. The valve, it will be observed, normally closes the pressure or delivery port P of the valve E from the central space or reservoir, since it cuts off communication between the port f and the port P, and it therefore normally opens said space or reservoir to the suction-port P'. These parts are all identical in construction and mode of operation with the construction disclosed in my prior application and need not be further described except to note the fact that the chambers on opposite sides of the valve V are connected to pipes 27 and 27', which afford communication through the relief-chamber between the ports P and P' and my adjusting mechanism now to be described. I may also note that instead of the worm-gearing in my prior construction for effecting movement of the gears which actuate the shafts and bushes for adjustment of the crank-pins to vary the speed I here use two racks W and Y, as particularly described herein-after. With this brief description of the essential parts of the speed-gear the application of my present invention thereto will be clearly understood and in the form in which I have embodied the invention in the present instance.

The numeral 10 indicates the cylinder of a fluid-pressure motor; 11, a piston adapted to operate in said cylinder; 12, the piston-rod; 13 and 13', the heads for the motor-cylinder; 14, a cylindrical casing mounted on the side of the motor-cylinder with its bore at right angles to the bore of the motor-cylinder and communicating therewith through passages 15 and 15'.

Mounted in the interior of the cylindrical casing 14 is a hollow cylindrical secondary valve 16, in one end of which is a head 17,

having a stem or boss to which a rod 18 is fastened. Secured to the rod 18 is a lever 19, adapted to impart a vibratory or oscillatory motion to the secondary valve 16 in the casing 14, while the other end of the lever 19 is so connected to the piston-rod 12 by the connecting-rod 20 and the pin 21 that the movements of the piston back and forth in its cylinder will cause the secondary valve 16 to be correspondingly rotated in the casing 14, such movements being simultaneous and synchronous. Mounted in the bore of the secondary valve 16 is a primary controlling-valve 22, containing the four sector cylindrical chambers 23, 23', 23'', 23''', formed by the webs 22', two of which, 23 and 23'', are open to one end of the casing 14—in the instance shown, left-hand end—and the other two, 23' and 23''', are open to the other end of the casing 14. Extending from one end of the valve 22 is a stem or boss to which a rod 24 is fastened, while the other end of the rod is provided with a controlling-lever 25, the latter of which is placed within convenient reach of the operator or connected to suitable operating means located at a distance, if desired. The two heads 26 and 26' close the ends of the cylindrical casing 14, while connected to these heads are the two fluid-circuit pipes 27 and 27', which connect the interior of the casing 14 with the two sides of the fluid-circuit, such connection in the instance shown being through the relief-chamber d and the ports s and s' and their connecting passages. The head of the secondary valve 16 has passages 28 cut through it to allow the passage of fluid. From the inner side of the head of the secondary valve 16 pins 29 and 29'' extend through the holes 30 and 30'' into the sector cylindrical chambers 23 and 23'' of the primary valve 22, these pins for reasons hereinafter pointed out being smaller than the holes in said valve through which they pass. The other two holes 30' and 30''' allow communication between the other two sector cylindrical chambers 23' and 23''' of the valve 22 and their end of the casing 14. The channels 32 and 32' are formed as separate recesses in the outer surface of the valve 16. Extending from one end of the piston-rod 12 are two racks W and Y, lying in different planes, rigidly connected together and meshing with their respective spur-gears O and Q and so placed with respect to their spur-gears that a rectilinear motion of the piston-rod 12 causes the two gears O and Q to turn in opposite directions. The ratio of the diameter of the spur-gear O to the diameter of the spur-gear Q is made equal to the ratio of the diameter of the internal gear R to the diameter of the spur-gear T.

The operation of the device is as follows: Suppose the pump-cylinders of the speed-gear to be driven by some outside source of power in the direction of the arrow, Fig. 1,

and all the other parts to be in the positions shown in Figs. 1, 2, and 3, where the piston of the adjusting-motor is at its mid-position and the primary and secondary valves at their mid or zero position and all the spaces in the adjusting-motor cylinder 10, the cylindrical casing 14, and the primary and secondary valves 22 and 16, respectively, are filled with fluid, a suitable supply of fluid under pressure, here shown as the pressure side of the fluid-circuit of the speed-gear, being connected to the pipe 27, while the pipe 27' is connected to the exhaust or suction side of the fluid-circuit. With the parts in the positions assumed suppose now that the primary controlling-valve 22 is given a slight rotary displacement—say in a clockwise direction, as viewed in Fig. 2—the ports 31 and 31' in the secondary valve will be partially uncovered, and fluid under pressure will then pass from the pipe 27 through the holes 28 in the head of the secondary valve, thence through the holes 30 and 30'' into the chambers 23 and 23'' of the primary valve, thence from the chamber 23 through the port 31, the channel 32, the passage 15, and into the outer end of the motor-cylinder 10. At the same time that communication is established between the pressure-supply pipe 27 and the outer end of the cylinder 10 by the clockwise rotation of the valve 22 the pipe 27', now acting as the exhaust, is put into communication with the inner end of the motor-cylinder 10, since the uncovering of the port 31' in the secondary valve establishes communication between the chamber 23''' and the channel 32', and fluid can then pass from the inner end of the motor-cylinder through the passage 15', the channel 32', the port 31', the chamber 23''', the hole 30''' in the end of the valve 22, and from thence through the clearance in the end of the chamber 14 into the exhaust-pipe 27' and back to the fluid-circuit of the speed-gear. The fluid under pressure then reaching the outer or left-hand end of the cylinder 10 acts against the piston and forces it toward the other or right-hand end of the cylinder; but at the same time that the piston moves the connecting-rod 20 acts on the lever 19, which rotates the secondary valve 16 in a clockwise direction, and the fluid-pressure continues to pass to the outer end of the cylinder 10 and to force the piston 11 toward the other end and the fluid out of the inner end of the cylinder 10 until the secondary valve 16 has been rotated in a clockwise direction equal in amount to that given to the primary controlling-valve 22, at which time the ports 31 and 31' are again covered by the primary valve 22, and no fluid can then pass to or from either side of the piston of the motor. Similarly, the piston of the motor will move to the other or left-hand end of the cylinder if the primary valve is given a slight rotation in a counter-clockwise direction and its movement

in this direction will cease when the secondary valve has been thereby rotated in a counter-clockwise direction equal in amount to the rotation of the primary controlling-valve within the limits of the device. If the motor-piston should pass beyond its proper position, it will carry the secondary valve also beyond its proper position, and then immediately the fluid under pressure will pass to the opposite side of the motor-cylinder and send the piston and the secondary valve back to their positions corresponding with the position of the primary controlling-valve. The pins 29 and 29", extending from the inside of the head of the secondary valve into the holes 30 and 30" in the primary valve, serve two purposes: first, to prevent too-rapid adjustments of the primary controlling-valve, and, second, should the supply of fluid under pressure at any time fail it would still be possible to move the piston back and forth in the motor-cylinder by rotating the primary valve 22 until the pins 29 and 29" in the head of the secondary valve 16 engage the sides of the holes 30 and 30" in the primary valve, when a further movement of the primary controlling-valve 22 in the same direction, by such means as a lever 25, connected to it through the rod 24, to which it is secured, would cause the secondary valve to be forced in the same direction, and the secondary valve, by its connection with the piston of the motor through the rod 18, the lever 19, connecting-rod 20, pin 21, and the piston-rod 12, would force the piston to a position corresponding with that of the primary controlling-valve less the amount of rotation necessary to give to the primary valve in order to make the holes 30 and 30" bear against the sides of the pins 29 and 29". When the piston of the motor-cylinder 10 moves toward the inner end, due to a clockwise rotation of the primary valve, the rack W causes the gear O to also rotate in a clockwise direction, and the internal gear R meshing with the spur-gear T causes the shaft N, to which it is fastened, to also turn in a clockwise direction, while at the same time the rack Y meshing with the gear Q causes the bush M, to which it is fastened, to rotate in a counter-clockwise direction, thus causing a proportional adjustment of the crank C of the speed-gear.

It will be clearly seen that with my invention when the adjusting-motor is supplied with a practically non-compressible fluid the piston and consequently all the parts to which it is connected are locked against any extraneous force tending to change their adjustment, since with the cylinder and all of the passages filled with the fluid and the primary valve covering the ports of the secondary valve it is impossible for the piston to force fluid from either end of the adjusting-motor cylinder. It will furthermore be seen that when the crank of

the pump of the speed-gear is at its zero or concentric position, at which point the pump ceases to furnish fluid under pressure, if the primary valve be moved until the holes 30 and 30" bear against the pins 29 and 29" in the head of the secondary valve the crank of the pump of the speed-gear will be moved from its zero position by a further movement of the primary or controlling valve, since such a further movement would cause the secondary valve 16 to move, which in turn would impart movement to the piston-rod 12 through the lever 19, the connecting-rod 20, and the pin 21, and thus cause the racks W and Y to turn the gears O and Q, and thereby adjust the crank. It will be further seen that the valve mechanism comprises two members, one of which is controllable at will and the other operates synchronously with the movable element of the motor, such as the piston, and that movement of the former member causes admission of fluid-pressure to one side of the piston or movable element, while the latter member is operated by the piston or movable element to close said admission, thereby causing the movement of the piston to correspond with the movement of the first member. It will also be readily seen that when that portion of the adjusting mechanism which comprises cylinder 10 and the valve mechanism is placed in such a position with relation to the plane of racks W Y that the controlling-lever 25 hangs in a vertical position, as in Fig. 3, it being apparent that such position may be obtained by rotating arm 21, the cylinder, &c., ninety degrees about rod 12, the said lever may be utilized to act as a controlling-pendulum, whereby any inclination of the device from normal position due to any cause whatever may cause the lever 25 under the influence of gravity to operate the controlling-valve 22, the movements of which in turn may cause the piston of the adjusting-motor to automatically effect suitable adjustments of the mechanism on which said motor acts.

It is of course understood that all joints, stuffing-boxes, &c., are to be packed in the usual manner, well known to those skilled in the art.

It is evident that while I have defined the primary valve as controlling the passage of fluid through the secondary valve and the primary valve as controllable at will such mode of operation may be reversed, and hence the terms "secondary" and "primary" as applied to the two valves are to be taken as relative terms, definitive rather of the mode of operation of the two coacting valves and not as to their relative positions.

I claim as my invention—

1. The combination with a variable-speed gear consisting of a pump and a motor, of a secondary fluid-pressure motor and connections between said motor and variable-speed

gear, whereby the speed-gear may be adjusted for different speeds, substantially as described.

2. The combination with a fluid-pressure-operated variable-speed gear consisting of a 5 pump and a motor, of a secondary fluid-pressure motor and connections between said secondary motor and variable-speed gear, whereby the speed-gear may be adjusted for different speeds, substantially as described.

10 3. The combination with a variable-speed gear consisting of a pump and a motor and having an element capable of being adjusted for different speeds, of a secondary fluid-pressure-actuated motor and means interposed 15 between the secondary motor and the said element whereby the motor may act through said interposed means to vary the relative position of the elements for different speeds, substantially as described.

20 4. The combination with a variable-speed gear consisting of a pump and a motor and having an element capable of being adjusted for different speeds, of a secondary fluid-pressure-actuated motor having its movable 25 element connected to the adjustable element of the speed-gear, a fluid-pressure supply and exhaust for said secondary motor, valve mechanism controlling admission and exhaust of motor fluid, and means controllable at will 30 for actuating the valve mechanism, one element of which operates synchronously with the movable element of the motor, substantially as described.

35 5. The combination with a variable-speed gear consisting of a pump and a motor and having an element capable of adjustment for varying the speed, of a secondary motor-cylinder having a piston therein, connections between said piston and the adjustable element 40 of said speed-gear, a fluid-pressure supply and exhaust for the motor, valve mechanism controlling said supply and exhaust consisting of two members, one controllable at will and the other operating synchronously with 45 the piston of the motor, whereby movement of the former causes admission of fluid-pressure to either side of the piston and the latter operates to close said supply when the piston has moved to a position determined by the position of the former, substantially as described.

50 6. The combination with a variable-speed gear consisting of a pump and a motor and having an element capable of adjustment for varying the speed, of a secondary motor-cylinder having a piston therein, connections between said piston and the adjustable element of the speed-gear, a fluid-pressure supply and exhaust for said secondary motor, valve mechanism controlling the same, comprising a primary member adjustable at will and a secondary member connected to the piston and operating synchronously therewith, whereby adjustment of the primary member to any position for admission of fluid-pressure to either side of the piston effects a

corresponding movement of the piston, substantially as described.

7. The combination with a variable-speed gear consisting of a pump and a motor adapted to be driven by said pump, a closed fluid-circuit between the pump and motor, said gear having an element capable of adjustment for varying the speed, of a secondary motor-cylinder communicating with the pressure and suction sides of the speed-gear, a piston in 70 said cylinder having its rod connected to the adjustable element, a valve-casing on the cylinder communicating with each end thereof and through which the fluid passes from and to the speed-gear, a primary valve in said chamber or casing movable at will, a secondary valve in said casing controlling the passage of fluid between the motor-cylinder and the speed-gear, and connections between the secondary valve and the piston-rod, substantially as de- 80 scribed.

8. The combination with a speed-gear consisting of a pump and a motor and having an element capable of and requiring adjustment, of a secondary fluid-pressure motor-cylinder, 90 a piston movable therein and connected to the adjustable element, a valve-casing on said cylinder communicating with each side of the piston and with a fluid-pressure supply, a rotary valve having its interior in communication 95 with the valve-casing and ports for establishing communication between the same and the motor-cylinder, connections between the piston and said valve, a rotary valve operating within the first valve and normally closing its 100 ports, and controllable at will, substantially as described.

9. The combination with a variable-speed gear consisting of a pump and a motor, of a motor cylinder and piston in a fluid-pressure- 105 adjusting mechanism, a valve-casing communicating with the cylinder at each side of the piston and with a source of fluid-pressure supply, a rotary valve mounted within and communicating with said casing and connected to 110 and moving with the piston, ports in the valve for establishing communication between its interior and the cylinder, a second rotary valve within the first valve controlling the passage 115 of fluid from the casing through the ports of the said first valve, and a locking device between the two valves adapted to establish a positive connection between them, so that movement of the second valve may impart positive movement to the first valve, substan- 120 tially as described.

10. The combination with the motor cylinder and piston in a fluid-pressure-adjusting mechanism, of a valve-casing communicating with the cylinder at each side of the piston 125 and with a source of fluid-pressure supply, a secondary valve connected to and moving with the piston and having ports controlling the passage of fluid from the casing to the cylinder, a primary valve normally closing said 130

ports, and a normally inactive positive connection between the two valves, substantially as described.

11. The combination with the motor cylinder and piston of a fluid-pressure-adjusting mechanism, of a valve-casing communicating with the cylinder at each side of the piston and with a source of fluid-pressure supply, a secondary valve connected to and moving with the piston and having ports controlling the passage of fluid from the casing to the cylinder, a primary valve normally closing said ports, and a fixed part carried by the secondary valve normally out of engagement with but adapted to engage with the primary valve, whereby movement imparted to either valve may be transmitted to the other, substantially as and for the purpose described.

12. The combination with the motor cylinder and piston in a fluid-pressure-adjusting mechanism, of a valve-casing communicating with the cylinder on opposite sides of the piston and with a source of fluid-pressure supply, a secondary rotary valve communicating with the casing and having ports adapted to establish communication between the casing and the cylinder, connections between the said valve and the piston, whereby the valve is moved synchronously with the piston, a primary rotary valve mounted within the secondary valve and controlling the ports in the secondary valve, said valve having chambers in communication with opposite ends of the casing, and a fixed part carried by one of the valves normally out of engagement with but adapted to engage the other valve, and means for moving the primary valve at will, whereby communication may be established through the ports of the secondary valve between the casing and the cylinder, substantially as described.

13. The combination with the cylinder and piston of a fluid-pressure-adjusting motor, of a casing in communication with each end of the cylinder and with a source of fluid-pressure supply, a secondary rotary valve in said casing having its interior in communication with each end of the casing, fluid-passages on its outer side adapted to connect with the opposite ends of the cylinder, ports connecting said passages with the interior of said valve, a primary rotary valve mounted within the secondary valve and communicating with each end of the casing and normally closing the ports in the secondary valve, and oppositely-disposed chambers in said primary valve communicating with the ends of the valve-casing, and a fixed part carried by one of the valves normally out of engagement with but adapted to engage the other valve, connections between the piston of the motor and the secondary valve, and means for actuating the primary valve, substantially as described.

14. The combination with a variable-speed gear having a relatively fixed element capa-

ble of adjustment, and spur-gears forming an element of the adjusting mechanism thereof, of a cylinder connected with a source of fluid-pressure supply having a piston therein, a yoke-rack connected to said piston, one set of teeth thereon engaging one spur-gear and the other set the other spur-gear to cause them to rotate in opposite directions, a valve mechanism comprising primary and secondary members for controlling the admission and exhaust of the cylinder, connections between the secondary valve and the piston, and means for operating the primary valve, substantially as described.

15. The combination with a mechanism having relatively fixed elements capable of and requiring adjustment, spur-gears forming elements in the adjusting means of said mechanism, of a yoke-rack having oppositely-disposed teeth engaging the gears to cause them to rotate in opposite directions, a motor-cylinder having a piston therein, a valve-casing communicating with a source of fluid-pressure supply and with the cylinder on opposite sides of the piston, a secondary valve in said casing and having ports therein adapted to control the passage of fluid to and from the cylinder, and a primary valve mounted within the secondary valve and controlling the passage of fluid from the casing through the secondary valve-ports, connections between the secondary valve and the piston, and means for operating the primary valve, substantially as described.

16. The combination with a fluid-actuated variable-speed gear provided with a pump, of a fluid-pressure motor actuated by the fluid-pressure generated in the speed-gear, and connections between said motor and speed-gear, whereby the speed-gear may be adjusted for different speeds, substantially as described.

17. The combination with a fluid-actuated variable-speed gear having an element capable of adjustment, of a fluid-pressure motor, valve mechanism interposed between the speed-gear and motor and controlling fluid-pressure between the speed-gear and the motor, one element of which valve mechanism is controllable at will and the other by the motor, and connections between the motor and the adjustable element of the speed-gear, substantially as described.

18. The combination with a fluid-actuated variable-speed gear having an element capable of adjustment, of a fluid-pressure motor deriving its fluid-pressure from the speed-gear, valve mechanism interposed between the speed-gear and the motor for controlling the flow of fluid between the two, said valve mechanism comprising a primary valve controllable at will, and a secondary valve having positive connections with the motor and arranged to cut off the supply of fluid-pressure from the speed-gear to the motor and stop the motor in a position determined by

the position of the primary valve, and a connection between the motor and the adjustable element of the speed-gear, substantially as described.

- 5 19. The combination with a variable-speed gear consisting of a pump and a motor adapted to be driven by said pump, a closed fluid-circuit between the pump and the motor, said gear having an element capable of adjustment 55
10 for varying the speed, of a secondary fluid-pressure motor having a movable element, connections between said movable element and the adjustable element, fluid connections between the pressure and suction sides of the 15 speed-gear and the secondary motor, valve mechanism between the motor and the speed-gear for controlling the passage of fluid through said fluid connections, and means controllable at will for actuating the valve mechanism, one element of which operates synchronously with the movable element of the 20 motor, substantially as described.
20. The combination with a variable-speed gear consisting of a pump and a motor and having 25 an element capable of and requiring adjustment, of a fluid-pressure-adjusting motor, a connection between said adjustable element and the motor, and means so disposed as to permit the action of gravity to control the 30 movements of the adjusting-motor, substantially as described.

21. The combination with mechanism having an element capable of and requiring adjustment, of a fluid-pressure-adjusting motor, 35 a valve mechanism controlling the supply of fluid to and from the motor, one element of said valve mechanism controllable at will and free to be moved by the action of gravity when the device is inclined from normal position, 40 and the other element connected to the motor and movable therewith, and a fixed part carried by one element of said valve mechanism, normally out of engagement with but adapted to engage with the other element, substantially 45 as described.

22. The combination with mechanism having an element capable of and requiring adjustment, of a fluid-pressure-adjusting motor, a connection between the adjustable element 50 of the mechanism and the motor, valve mechanism controlling the supply of fluid to and

from the motor, said valve mechanism comprising a primary valve having a dependent operating-stem normally vertical by which the said valve may be adjusted at will, and a secondary valve connected to and operated by the motor and whose position is determined by the position of the primary valve, and a fixed part carried by one of the valves, normally out of engagement with but adapted to engage 60 the other valve, substantially as described. 55

23. The combination with mechanism having an element capable of and requiring adjustment, of a fluid-pressure-adjusting motor, connection between said motor and the mechanism to be adjusted, a valve mechanism controlling the supply of fluid to and from the motor consisting of a primary rotary valve having an arm normally vertical and adapted to be moved by gravity when the device is inclined from the normal or level position, and a secondary valve controlling the passage of fluid from the primary valve to and from the motor, and connection between the secondary valve and the motor for causing the two to 70 operate synchronously, and a fixed part carried by one of the valves, normally out of engagement with but adapted to engage the other valve, substantially as described. 75

24. The combination with a variable-speed gear comprising a pump, a motor, and a mechanism having an element capable of and requiring adjustment, of a secondary fluid-pressure-adjusting motor, connection between the motor and the said mechanism, a valve mechanism controlling the supply of fluid to and from said motor, one element of said valve mechanism adjustable at will and the other element thereof connected to the said motor and movable therewith, a fixed part carried 80 by one of said elements of the valve mechanism normally out of engagement but adapted to engage with the other element, substantially as described. 85

In testimony whereof I have signed my name 90 to this specification in the presence of two subscribing witnesses.

CHARLES M. MANLY.
